CRANKCASE FOR MULTIPLE BANK RADIAL MOTORS

Ferdinand Brandner, Dessau, Germany, assignor to Junkers Flugzeug-und-Motorenwerke Aktiengesellschaft, Dessau, Germany, a corporation of Germany

Application September 6, 1938, Serial No. 228,474
In Germany September 6, 1937

8 Claims. (Cl. 123—55)

This invention relates to improvements in crankcases for multiple bank radial motors which are primarily adapted for use on airplanes.

It is an object of the invention to provide a crank whereon all the cylinders are supported so that the case and the cylinders together form a thoroughly rigid unit which will, without perceptible distortion, withstand all the stresses to which it is subjected when the motor is in operation; and wherein the weight of the motor and the said stresses are transferred to the airplane fuselage or other support on which the motor is mounted.

I am aware that crankcases for multiple bank radial motors have already been made which were split, either transversely of the crank shaft axis or in alignment therewith. In both cases however, satisfactory utilization of these forms of construction has been limited to motors having only quite a small number of cylinders, primarily because no satisfactory way has been found to make such crankcases carrying a greater number of cylinders sufficiently rigid within permissible weight limits.

Another object of the invention is then to provide a crankcase for multiple bank radial motors which is split longitudinally parallel with the crank shaft axis and a spaced vertical distance therefrom, and consists of a larger substantially U-shaped portion and a smaller portion; wherein most of the cylinders are carried by the larger portion and the remainder by the smaller portion; and wherein the two crankcase portions are so secured to one another that no perceptible movement of one portion relative to the other occurs even in motors having a large number of banks.

Further objects of the invention are to provide a crankcase for multiple bank radial motors which is relatively simple to manufacture and assemble, and light in weight; wherein a crank shaft and its connecting rods may be quickly and easily installed or removed; and wherein the crankcase and the radially disposed cylinders form a structure which is tubular in cross section thereby adding to its rigidity.

Having thus briefly stated some of the major objects and advantages of the invention, I will now proceed to describe two preferred embodiments of the invention with the aid of the accompanying drawings, in which:

Figure 1 is a cross section on the line 1—1 of Figure 2, showing a crankcase for multiple bank

radial motors having six radially disposed cylinders in each bank.

Figure 2 is a longitudinal section on the line 2—2 of Figure 1.

Figure 3 is a cross sectional view showing a somewhat modified arrangement for radial motors having their cylinders arranged in banks of nine.

Referring now to Figures 1 and 2. Figure 1 shows a bank of six cylinders 1, 2, 3, 4, 5 and 6 radially disposed to one another; and from Figure 2 wherein the cylinders 3a, 3b, 3c, 3d, 4a, 4b, 4c, 4d, 5a, 5b, 5c and 5d are shown it becomes evident that this motor is provided with four banks of cylinders, though it is understood that both the number of banks and the number of cylinders in each bank are subject to considerable variation. All the cylinders of all the banks are carried by a common crankcase 7 which is tubular in cross section and split longitudinally along a joint 8 parallel with the axis of the crank shaft bearings 15 and spaced a vertical distance a therefrom, thereby forming a larger portion 1a, which is substantially U-shaped in cross section, and a smaller portion 1b. The cylinders 1, 2, 3 and 4 of all the banks are carried by the larger portion 1a and the remaining cylinders 5 and 6 of all the banks by the smaller portion 1b. The two crankcase portions 1a and 1b are secured to one another by suitable fastening means such as the bolts 9, and are reinforced at right angles to the said crank shaft bearing axis by walls 10 and 11 respectively formed integral with their respective portions.

Formed integral with the larger crankcase 35 portions 1a are a plurality of crank shaft bearings 15 having laterally opposed guides 16 between which covers 17 are inserted. 18 denotes studs in threaded engagement with the bearings 15 which pass through the covers 17 and have nuts 18a on their outer extremities by which the said covers are securely held in position. Extending transversely through each pair of guides 16 and through the cover 17 between them is a draw bolt 19 which performs a dual function; it both acts as a dowel to prevent substantially radial movement of the cover 17 and also forces the guides 16 towards one another into intimate contact with the adjacent lateral faces of the said cover, thereby reinforcing the structure and providing a thoroughly rigid bearing. The latter point is of prime importance because the provision of a crankcase of utmost rigidity is a necessity for the successful operation of this type of motor. In this connection it may also be re-

marked that the tops of the bearings 17 lie substantially in line with the joint 8, so that the inner edge faces of the ribs 11 may be slightly spaced from the covers without weakening the 5 said ribs or reducing the strength of the assembled structure. It will also be seen that the smaller crankcase portion 1b and the bearing covers 17 may be readily removed so that a crank shaft (not shown) mounted or to be mounted in 10 the bearings 15 may be readily removed or inserted.

As can be clearly seen in Figure 2 all the cylinders in each bank are in longitudinal alignment with one cylinder in every other bank, and each 15 row of cylinders thus constituted, for instance the cylinders 3a, 3b, 3c and 3d, is parallel to the axis of the crank shaft bearing 15. Again each of the rows of cylinders is preferably formed in a single block to increase the strength of the structure.

Formed integral with the larger crankcase portion 1a and extending longitudinally thereof are a plurality of water jackets 26, 27, 28 and 29 radially disposed to the crank shaft bearing 15. 25 Each of these water jackets supports one cylinder of each bank, for instance, as may be seen in Figure 2, the cylinders 3a, 3b, 3c and 3d are all carried by the water jacket 28. Similarly the water jackets 30 and 31 are each integral with the 30 smaller crankcase portion 1b, and each carries one cylinder of each bank as shown in the aforesaid view wherein the cylinders 5a, 5b, 5c and 5d are carried by the jacket 30. It is of course understood that the cylinders 1, 2, 3, 4, 5 and 6 are made integral with their respective water jackets 26, 27, 28, 29, 30, and 31 which are frequently cast around them, though any other preferred means of obtaining absolutely rigid connections between the water jackets and the cylinders supported by them may be employed when desired.

32 denote radial ribs which extend between and are integral with adjacent pairs of water jackets 26, 27, 28 and 29, and 30 and 31, upon the larger and smaller crankcase portions 1a and 1b respectively. 20, 21, 22, 23, 24 and 25 indicate cylinder heads upon the cylinders 1, 2, 3, 4, 5 and 6 respectively.

Figure 3 illustrates a cross sectional view of a modified arrangement of the invention wherein a plurality of banks of nine radially disposed cylinders are employed. The crankcase 40, which is also of tubular cross section, again consists of a larger portion 40a and a smaller portion 40b 55 joined to one another in a plane parallel to the axis of the crank shaft bearings 55 and spaced a vertical distance a therefrom.

In this case the cylinders 41, 42, 43, 44, 45 and 46 of all the banks are carried by and integral 60 with the larger crankcase portion 40a which is again U-shaped in section, and the remaining cylinders 47, 48 and 49 are carried by and integral with the smaller portion 40b. Between adjacent radial pairs of cylinders on both housing portions spaced inner and outer walls 40c and 40d are provided which extend lengthwise of the crankcase and complete the tubular cross sectional form. These walls not only reinforce the structure and further increase its rigidity 70 but also provide passages 59 between them which extend longitudinally of the crankcase and may be utilized as pipe conduits or for any other purpose.

Mounted upon the crank shaft bearings 55, 75 which are integral with the larger crankcase por-

tion 40a, are covers 54 transversely across the tops of which contact surfaces 53 are provided. Formed integral with the smaller crankcase portion 40b are a plurality of transverse walls 50 which project inwardly and terminate in ribs 51 across the edge faces of which contact surfaces 52 are formed to bear against the said surfaces 53. Studs 56, which project from the bearings 55 extend through the covers 54 and also through pillars 50a formed upon opposite edges 10 of the walls 50. Nuts 57 threaded upon the studs 56 intermediately of their height hold the covers 54 in position, and nuts 58 upon the outer extremities of the said studs bear against the ends of the pillars 50a and force the contact 15 surfaces 52 into intimate contact with the contact surfaces 53.

The transverse walls 50 are also provided with laterally opposed pads 61 which are in alignment with opposed pairs of bearing cover guides 20 65 integral with the larger crankcase portion 40a. These pads extend between steps 62 formed upon the outer portion of the larger crankcase portion 40a and opposed faces 63 of the adjacent guides 65. Extending through the steps 62, the 25 pads 61, the guides 65 and the covers 54 are aligned passages 64 through which draw bolts 66 project, and press all these parts firmly together. The draw bolts 66 are disposed transversely of the axis of the bearings 55 and also 30 at right angles to the bolts 9 which extend through the joint of the two crankcase portions and hold the said portions together.

While in the foregoing two constructions of my invention have been described and shown, it is understood that the invention is susceptible to such further alterations and modifications as fall within the scope of the appended claims.

What I claim is:

1. A crankcase arrangement for multiple bank radial motors comprising a crankcase having crank shaft bearings integral therewith, said case being split parallel with the bearing axis a spaced vertical distance therefrom whereby said case is divided into a larger and a smaller portion, means securing said portions to one another, all said bearings being integral with the larger portion, opposed guides on said bearings, a cover mounted on each bearing between the opposed guides, bolts extending through each opposed pair of guides and the cover between them holding said parts immovable, and banks of radially disposed cylinders carried by the crankcase.

2. A crankcase arrangement for multiple bank radial motors, comprising a tubular crankcase 55 having crank shaft bearings integral therewith, said case being split parallel with the bearing axis a spaced vertical distance therefrom thereby dividing the case into a larger portion with which all the bearings are integral and a smaller 60 portion, laterally opposed guides on each bearing, a cover on each bearing between each opposed pair of guides, a transverse wall on said smaller portion extending across each bearing, said walls having laterally opposed pads thereon 65 extending between the tubular wall of the larger crankcase portion and the adjacent guides, and fastening means extending through the tubular wall, pads, guides and covers whereby the two crankcase portions and the bearing covers are 70 held immovable, and banks of cylinders radially disposed on said crankcase.

3. In a crankcase arrangement for multiple bank radial motors, the combination set forth in claim 2, wherein the inner edge faces of the

transverse walls between the pads bear upon said covers, and means holding said edge faces in firm engagement therewith.

4. A crankcase arrangement for multiple bank radial motors comprising a crankcase having crank shaft bearings integral therewith, said case being split parallel with the bearing axis a spaced vertical distance therefrom whereby said case is divided into a larger and a smaller portion, means securing the portions to one another, all said bearings being integral with the larger case portion, covers mounted on the bearings, inwardly projecting transverse walls integral with the smaller case portion extending substantially the full depth thereof across said covers at right angles to the bearing axis, the tops of said covers being substantially in alignment with the joint between the crankcase portions, and means holding substantially the full depth thereof across said covers at right angles to the bearing axis, the inner edge faces of the transverse walls bearing upon said covers and the tops of said covers being substantially in alignment with the joint between the crankcase portions, and means holding said inner edge faces securely against said covers.

5. A crankcase arrangement for multiple bank radial motors comprising a crankcase having crank shaft bearings integral therewith, said case being split parallel with the bearing axis a spaced vertical distance therefrom whereby said case is divided into a larger and a smaller portion, means securing the portions to one another, all said bearings being integral with the larger case portion, covers mounted on the bearings, inwardly projecting transverse walls integral with the smaller case portion extending substantially the full depth thereof across said covers at right angles to the bearing axis, the tops of said covers being substantially in alignment with the joint between the crankcase portions, and fastening means engaging the bearings and extending through said covers and transverse walls to hold the former upon the bearings and the edge faces of the latter upon the covers.

6. A crankcase arrangement for multiple bank radial motors comprising a crankcase having

crank shaft bearings integral therewith, said case being split parallel with the bearing axis a spaced vertical distance therefrom whereby said case is divided into a larger and a smaller portion, means securing the portions to one another, all said bearings being integral with the larger case portion, covers mounted on the bearings, inwardly projecting transverse walls integral with the smaller case portion extending substantially the full depth thereof across said covers at right angles to the bearing axis, the tops of said covers being substantially in alignment with the joint between the crankcase portions, studs extending from the bearings through the covers and transverse walls, nuts upon said studs intermediate their length securing the covers on the bearings, and nuts upon the outer extremities of the studs holding the edge faces of the transverse walls in contact with the tops of the covers.

7. A crankcase arrangement for multiple bank radial motors, comprising a tubular crankcase having crank shaft bearings integral therewith, said case being split parallel with the bearing axis to thereby divide it into a larger portion and a smaller portion, laterally opposed guides on each bearing, a cover on each bearing between each opposed pair of guides, a transverse wall on said smaller portion extending across each bearing, said walls having laterally opposed pads thereon extending between the tubular wall of the larger crankcase portion and the adjacent guides, and fastening means extending through the tubular wall, pads, guides and covers whereby the two crankcase portions and the bearing covers are held immovable, and banks of cylinders radially disposed on said crankcase.

8. In a crankcase arrangement for multiple bank radial motors, the combination set forth in claim 7 wherein the inner edge faces of the transverse walls between the pads bear upon said covers, and means holding said edge faces in firm engagement therewith.

FERDINAND BRANDNER.
